UNITED STATES PATENT OFFICE

147,611

DESIGN FOR A BAR CABINET

Alexander E. Brenner, Columbus, Ohio

Application November 27, 1945, Serial No. 124,103

Term of patent 14 years

(Cl. D33—19)

To all whom it may concern:

Be it known that I, Alexander E. Brenner, a citizen of the United States, residing at Columbus, in the county of Franklin and State of Ohio, have invented a new, original, and ornamental Design for a Bar Cabinet, of which the following is a specification, reference being had to the accompanying drawing, forming a part thereof.

Fig. 1 is a perspective view of a bar cabinet in its closed state showing my new design;

Fig. 2 is a similar view disclosing the cabinet when opened.

The other side and rear portion of the cabinet are approximately plain.

I claim:

The ornamental design for a bar cabinet, substantially as shown and described.

ALEXANDER E. BRENNER.
